UNITED STATES PATENT OFFICE.

GUY E. TIFFT, OF DETROIT, MICHIGAN, ASSIGNEE, BY MESNE ASSIGNMENTS, TO
FITNEY-BOWES POSTAGE METER COMPANY, OF STAMFORD, CONNECTICUT, A COR-
PORATION OF DELAWARE.

ENVELOPE SEALING AND STAMPING MACHINE.

Application filed September 20, 1920, Serial No. 411,465. Renewed March 5, 1925.

To all whom it may concern:

Be it known that I, GUY E. TIFFT, a citizen of the United States of America, residing at Detroit, in the county of Wayne and State of Michigan, have invented certain new and useful Improvements in Envelope Sealing and Stamping Machines, of which the following is a specification, reference being had therein to the accompanying drawings.

This invention relates to automatic envelope sealing and stamping machines and more particularly to machines designed to effect the sealing and stamping of an envelope without interrupting the travel of the envelope through the machine.

The invention consists in the various structural features and arrangement of parts hereafter fully set forth and illustrated in the accompanying drawings; wherein,

Figure 1 is a plan view partly in section of the improved sealing and stamping machine, the casing of the stamp feeding mechanism being omitted.

Figure 1^a is a section taken on line 1^a—1^a of Figure 1;

Figure 2 is a front view of the machine;

Figure 3 is a longitudinal sectional view the section being taken on line 3—3 of Figure 1;

Figure 3^a is a fragmentary sectional view of a portion of Figure 3 drawn to an enlarged scale;

Figure 4 is a rear view of the machine with the rear cover member removed;

Figure 5 is a fragmentary plan view of the envelope feed plate, showing also the end portion of the machine to which said plate is attached;

Figure 6 is a cross section view, the section being taken on line 6—6 of Figure 1;

Figure 7 is a detail perspective view of a trip mechanism which is actuatable by the envelope in its travel through the machine and which controls the stamp feed mechanism;

Figure 8 is a perspective view of the stamp feed mechanism;

Figures 9 and 10 are, respectively, perspective detail views of two members forming a guide member through which a strip of stamps is adapted to be fed;

Figure 11 is a perspective view of the

carriage for actuating travel of the stamp strip, showing the bracket, which mounts said carriage, but omitting the guide member through which the stamp strip feeds;

Figure 12 is a detail view of the clutch through which the stamp feeding mechanism is actuatable;

Figure 13 is a detail plan view of the ends of a series of spring fingers showing the staggered relation of said ends;

Figure 14 is an enlarged view in side elevation and partial section of the stamp feeding mechanism, showing the carriage advanced in full lines and retracted in dash lines.

In these views the reference character 1 designates the base of the machine, preferably a casting, and 2 and 3, respectively, designate the side casing members of the machine, the same being preferably formed of heavy sheet metal and rigidly secured to the base in any suitable manner. As will presently be described in detail, the envelope feed rollers and other main elements of the mechanism are supported by and arranged between the side plates 2 and 3, while the drive mechanism for said rollers and other elements is primarily mounted adjacent the exterior face of the plate 3, said mechanism being normally concealed and protected by a cover plate 4, secured in any suitable manner to the plate 3, and spaced therefrom sufficiently to form a chamber 5 to receive said drive mechanism.

At one end of the machine a pair of initial envelope feed rollers 6 are adjacently mounted upon a shaft 7, and at the opposite end, a pair of final feed rollers 8 and 8^a are mounted one above the other upon shafts 9 and 10, respectively. Intermediate the extremities of the machine, there are provided in suitably spaced relation two pairs of envelope feed rollers 11 and 12, mounted respectively upon shafts 13 and 14. All of the shafts 7, 9, 10, 13 and 14 are journaled at their extremities respectively in the plates 2 and 3, with the exception of the uppermost shaft 13.

The initial feed rollers 6 have their top portions projecting through an aperture 15 in a feed table 16, which is detachably secured in any suitable manner to the plates 2 and 3, and upon said upper projecting por-

tions of said rollers there bears a sheet metal guide finger 17 which is intermediately pivoted at 18 upon a bracket 19 carried by the plate 3 (see Figures 3 and 5). A coiled 5 spring 20 is compressed between the upper end of said guide finger and the bracket supporting the same to maintain a pressure of said finger upon the rollers 6 and the tension of said spring is regulable by an adjustment nut 21. A rubber brush member 22 is suitably secured to the guide finger 17 and projects into close proximity to the rollers 6 bridging the space interval between said rollers. Adjacent one edge of the table 10 16 there is secured to said table an upstanding flange 23, the upper edge of which is gradually inclined downwardly toward the aperture 15, said flange forming a guide for the flaps of the envelopes, as the same are fed to the rollers 6. 24 indicates a vertical guide plate for the closed bottom edges of the envelopes, said plate being provided with a supporting foot 25 resting upon the table 16 and being further supported by a rod 26 15 25 which telescopes within a sleeve 27 secured to the bracket 19. By inserting said rod more or less within the sleeve 27 the guide plate 24 may be adjusted in various spaced relations to the guide flange 23 so as to 30 adapt envelopes of various widths to be fed into the machine. A set screw 28 is mounted upon the sleeve 27 and is adapted to be tightened against the rod 26 to maintain any desired position of adjustment of the 35 guide plate 24. Upon the latter plate there is carried a horizontal pin 29 which projects transversely above the table 16 and is adapted to form a support for the rear portions of the envelopes, (indicated at 29^a 40 in Figure 4) as the latter are fed to the rollers 6, so as to incline said envelopes downwardly toward the rollers. Pin 29 is adjustable longitudinally of the plate 24 in a slot 30 of said plate and may be held adjusted at any desired point in said slot by a clamping nut 31. For shorter lengths of envelopes it is desirable to advance said pin toward the feed rollers 6, while in feeding comparatively long envelopes said pin is adjusted 45 50 remote from the feed rollers in said slot.

All of the described feed rollers are manually actuatable in common by a crank 32 which is mounted upon the shaft 14 of the lower roller 12 outside of the plate 2. From 55 said shaft, the shaft 13 of the upper roller 11 is driven by a chain 33, within the chamber 5, (see Fig. 4) which also drives a stub countershaft 34. From the latter shaft a chain 35 transmits the drive to the shaft 7 60 of the initial feed rollers. Another chain 36 driven by said lower shaft 14 transmits a drive to the upper shaft 14 and also to the shafts 9 and 10 of the final feed rollers. All 65 of the described mechanisms which are best illustrated in Figure 4, are located in the

chamber 5, formed between the detachable cover member 4 and the side plate 3.

The envelopes, after being successively fed between the initial rollers 6 and coacting 70 guide finger 17, encounter the upper portion of a rotative dished disc 37 which is mounted, with its stub shaft 38 inclined transversely of the machine, almost directly beneath the feed rollers 11, and which has its lower portion immersed within a water vessel 39. Said disc is so proportioned in size and so located and inclined that the inner or gummer surface of the flap of each envelope, as the latter is fed into engagement with the rolls 11, comes into contact 75 with the under face of said disc at the raised side of the latter.

In order to effect this result, the edge 39^a of the table 16, over which edge the flap of the envelope hangs as the envelope advances past the rollers 6, is arranged in a substantially tangential relation to the upper edge of the flap moistening disc 37. The stub shaft 38 of said disc is mounted in a bracket 40 which depends from a sheet metal arm 41 secured to the side plate 2 and projecting inwardly therefrom above the disc 37, said arm also providing a journal for the inner end of the lower shaft 13. Said stub shaft is adapted to be driven through a pair of beveled gears 42 from a shaft 43 arranged beneath the feed rollers 11. Said shaft and also the shaft 13 of the lower roller 11 are driven in common by a chain 43^a directly 80 from the lowermost shaft 14, this chain being arranged preferably close adjacent the inner face of the side plate 2. To insure a firm and positive engagement of the gummer surface of the envelope flap with the moist under face of the disc 37, a plurality of 85 spring fingers 44 are mounted upon the side plate 3 and arranged to bear terminally upon the under face of said disc at the point where the envelope flap passes beneath the disc. The tank 39 preferably is detachably 90 mounted within a correspondingly shaped opening 45 formed in the base 1 and normally is retained in said opening by a U-shaped wire support 46, the connecting portion 46^a of said wire being engageable with 95 a lateral face of the base. It is necessary to maintain the envelope-engaging upper portion of the disc 37 only slightly moist to sufficiently soften the adhesive upon the flap of the envelope, and consequently it is desirable to prevent the water in the vessel 39 rising too freely upon the flap-engaging under face of said disc. This object is attained 100 by engaging said face of the disc at a point just above the liquid level in said vessel by a brush 47 formed of rubber or other suitable flexible material (see Figure 1^a) said brush being pivoted upon a bracket 48 rising from the base 1 and being acted upon by an 105 adjusting nut 48^a mounted upon a screw 48^b 110 115 120 125 130

for regulating the degree of pressure exerted upon the disc. As there may also be a tendency for the liquid in the vessel 39 to rise upon the upper face of the disc 37 and thereby transmit excessive moisture to the envelope flap, a rubber or other flexible brush 49 is arranged to bear upon a peripheral portion of the upper face of said disc just above the liquid level in the vessel 39. As travel of an envelope through the rollers 11 carries the flap thereof beyond the disc 37, said flap is engaged by a spirally curved guide strip 50, (best shown in Figure 7) which is interiorly secured to the side plate 3 and tends to gradually deflect the flap upwardly against the body of the envelope, said strip being extended preferably from a point slightly in advance of the spring fingers 44 into close proximity to the final feed rollers 8 and 8^a. Between the two pairs of intermediate feed rollers 11 and 12 there is extended a table member 51 upon which the envelopes advance in their travel intermediate said rollers. While travelling across the table 51, the envelopes are held down in close proximity to said table by a horizontal guide plate 52 projecting from the side plate 3, and spaced slightly above said table.

The forward edge of each envelope, just after passing through the second pair 12, of intermediate feed rollers, engages a trip mechanism controlling the advancing of a strip of stamps, the cutting-off of the end stamp from said strip, and the delivery of the severed strip to moistening rolls and subsequently to rolls for affixing the stamp to the envelope. Describing now this provision for automatically stamping the envelopes and referring to Figures 3 and 8, 53 is a bracket mounted upon an upward extension 53^a of the side plate 3 said bracket sloping downwardly at a gradual inclination toward the delivery end of the machine and being secured to the extension 53^a by a vertical flange 53^b. Said bracket forms a support for a guide member through which a stamp strip 55 is threaded, and furthermore carries a carriage reciprocatory in the direction of inclination of the bracket. Adjacent the higher end of said bracket there is mounted upon a pin 57 a reel 58, upon which the stamp strip 55 is rolled, said reel being provided with a handle 59 to facilitate initial winding of the strip thereupon. Said guide member (see Figures 9 and 10) is formed of two sheet metal members 60 and 61, respectively the former resting directly upon the bracket 53 and having one end bent to form a spring clamping member 62 and engagement beneath the upper end of said bracket, and having upstanding flanges 63 along its lateral edges, providing a guide way for the strip 55. Said flanges adjacent the raised end of the guide member are formed respectively with tongues 63^a projecting to-ward each other, which tongues are engageable by a return-bent spring clamping member 64 formed upon the corresponding end of the member 61. The latter member has the nature of a leaf spring which is extended a considerable distance upon the underlying member 60 between the flanges 63 of the latter and is adapted to exert a moderate pressure upon the stamp strip to restrain the latter against any accidental travel. The carriage which forms the means for effecting a step-by-step advance of the strip 55 comprises a plate 65, slidably engaging beneath the bracket 53 and provided at its upper end with a pair of opposed upstanding lugs 66, one adjacent the outer edge of the bracket and the other passing through a slot 66^a in said bracket adjacent the flange 53^b. Said lugs carry a pin 67 extending transversely above the bracket 53 and spaced sufficiently above the latter to clear the guide members 60 and 61. Upon said pin is pivoted an apertured sheet metal frame 68 which projects downwardly toward the delivery end of the machine and which forms a mounting for a plurality of parallel spring fingers 69 formed of fine wire, said fingers being fixedly secured to the frame 68 adjacent its pivoted end and having their other extremities 69^a free and downwardly bent adjacent the lower end of said frame and respectively projecting through notches 70 formed in said end. Both members 60 and 61 of the guide member are formed with large elongated rectangular openings 70^a to permit the downturned ends of said fingers 69 to bear upon the stamp strip, for engagement with one of the usual lines of perforations 70^b, which separate the respective stamps of said strip when registered with such a line. A wire spring 70^c is coiled upon the pin 67 and exerts a downward pressure upon the frame 68 tending to constantly project the bent ends 69^a of the fingers 69 into a positive contact with the stamp strip which extends through the guide member beneath said fingers. It is to be noted that said ends of said wire fingers 69 are slightly staggered out of accurate alignment transverse of the fingers, as is indicated in Figure 13, so that certain of said ends will engage with certain of the perforations between two stamps of the strip even if for any reason the perforations are so formed as not to permit all of said ends to engage therewith. Adjacent to its pivotal end, the frame 68 is integrally formed with a thumb rest 71 which, when depressed, serves to raise said frame and the fingers 69 to permit the stamp strip 55 to be moved without interference therewith by the spring 70^c. At its lower end, the carriage is provided with a pair of opposed standards 72, projecting upwardly from the plate 65, one adjacent the outer edge of the bracket 53 and the other passing through the slot 66^a.

Said standards form a guideway for a stamp-severing knife 73 which is reciprocatory above the bracket 53 in a direction perpendicular to said bracket and which is normally held raised slightly above the stamp strip by a pair of coiled springs 74. The standards 72 are respectively formed at their upper ends with parallel angular extensions 75 between which is mounted a pin 76 forming a pivotal support for a bell crank comprising a relatively long upwardly projecting arm 77 slotted terminally as indicated at 78, to engage a pin 78^a projecting from the plate 53^a, and a short arm 79 projecting toward the knife 73 and carrying a spring pressed sliding dog 80 which is adapted to engage above said knife when the latter is in its raised position and forms a means for actuating the knife downwardly when said bell crank is rocked due to travel of the carriage toward the delivery end of the machine. When the carriage is returned to its normal position, shown in Figure 3, the resultant rocking of the bell crank 77, 79 returns the dog 80 to its normal position above the knife 73, said dog bearing against the knife during its upward movement and yielding against the pressure of its spring to permit such movement.

30 The sheet metal frame 68 carries a pin 81 projecting toward the bracket flange 53^b (see Figure 11), which pin is engageable, during the travel of the carriage toward the delivery end of the machine with a cam strip 82 carried by said flange, said strip acting upon said pin to gradually swing said frame upwardly about its pivot pin 67 so as to eventually disengage the fingers 69 from the stamp strip. The arrangement is such that at the instant said fingers are disengaged from said strip the knife 73 severs the strip at the line of perforations next in advance to that line which was engaged by said fingers. In other words, the down-turned extremities 69^a of the fingers 69 are spaced from the edge of the knife 73 exactly the width of one stamp of the strip 55, and when said strip is being advanced toward the delivery end of the machine by the carriage 56, the fingers 69 engage the strip at a distance from the end thereof equal to two stamps, while the knife 73 upon each engagement with said strip cuts off the end stamp thereof. Upon the return movement of the carriage it is necessary to prevent engagement of the fingers 69 with the stamp strip so as to avoid corresponding retractive movement of the stamp strip. This result is effected by providing a second cam 83 which is pivoted at 84 upon the flange 53^b and is spring pressed against the raised end portion of the strip 82 and which rises and falls as the pin 81 passes thereunder in completing its upward travel along the cam strip 82. During the return movement of the carriage said pin 81 rides upon the pivotal cam strip 83 and is thereby maintained at a sufficient elevation to permit the wire fingers 69 to fully clear the stamp strip. Just as the carriage completes its return movement, however, the pin 81 rides free of the cam strip 83, allowing the sheet metal frame 68 to swing down to its normal position, engaging the wire fingers 69 with the stamp strip. When the carriage is in the described retracted position, which it normally occupies, the down-turned ends 69^a of the wire fingers engage the stamp strip slightly to the rear of the second line of perforations 70^b from the end thereof so that upon the next advance movement of the carriage said fingers will engage said line of perforations immediately after such movement has begun.

35 It is preferred to utilize the rocking movement of the bell crank 77, 79 to actuate a counter 85 for registering the number of stamps which are severed from the strip 55, this result being accomplished by extending a link 86 from the arm 77 of said bell crank to an arm 87 carried by the counter. Thus, each time the carriage 56 is reciprocated the resultant rocking movement of the bell crank 77, 79 is transmitted through the link 86 to the arm 87 so as to advance the counter one unit.

40 Actuation of the carriage is effected by a pin 88 engaging the forward or lower end of said carriage and projecting through an inclined slot 89 in the extension plate 53^a. Adjacent the outer face of said plate said pin is engaged with one end of a connecting rod 90 which at its other end is provided with a collar 91 freely embracing an eccentric 92 mounted loosely upon the shaft 9 of the upper final feed roller 8. Said eccentric is adapted to be driven through a slotted collar 93 by a clutch member 94 provided with tongues 95 permanently engaging in the slots of the collar 93. The clutch member 94 coacts with a clutch member 95^a formed integrally with a sprocket wheel 96 which is fast upon the shaft 9 and is driven by the chain 36. The two clutch members 94 and 95^a are provided with ratchet teeth through which the latter is adapted to drive the former when said teeth are permitted to engage. A coiled spring 97 is compressed between the eccentric 92 and the clutch member 94 and tends to maintain driving engagement between the two clutch members. A bell crank lever 98 is pivoted at a point 99 beneath the eccentric 92, one arm of the lever projecting upwardly and terminating in a curved tapering finger 100 which bears upon the clutch member 94 and is adapted to normally retain said clutch member out of engagement with its fellow 95^a by acting upon a pin 100^a projecting radially from said clutch member 94. spring 101 acts upon said bell crank lever 98 to maintain pressure of the finger 100 against said clutch member. The other arm of the bell crank lever is terminally engageable by a trip arm 102 mounted upon one end of a rock shaft 103 and acted upon by a coiled spring 104 to maintain said arm normally raised sufficiently to permit the bell crank to occupy its normal position shown in full lines in Figure 4. Upon a slight rocking movement of the shaft 103 the arm 102 is caused to exert a downward pressure upon the bell crank 98, rocking the latter sufficiently to disengage its upper end 100 from the pin 100^a, as shown in dash lines in Figure 4, thus permitting the spring 97 to throw the clutch member 94 into driven engagement with the clutch member 95. The shaft 103 has its extremities respectively journaled in the side plates 2 and 3 and at an intermediate point carries a tripping plate 105 projecting rigidly upward. Said plate carries a substantially vertical trip arm 106, the same being mounted upon a pair of swinging links 107, one of which is acted upon by a coil spring 107^a to maintain said arm normally projected at its upper end slightly above the feed table 51 so as to lie in the path of the envelopes as the same advance from between the intermediate rollers 12. Said trip arm, when encountered by an advancing envelope, is swung forwardly and downwardly together with the plate 105, rocking the shaft 103 in opposition to the spring 104 which latter is relatively weak and causing the arm 102 to rock the bell crank lever 98 sufficiently to draw the finger 100 clear of the pin 100^a. This permits the two clutch members 94 and 95^a to engage and thus provides for actuation of the carriage.

Just before completion of each advance movement of the carriage, and just prior to severing of the terminal stamp from the strip 55, said stamp is engaged between a pair of small feed rollers 108, the lowermost of which is immersed, with the exception of its upper portion in a small water tank 109. These rollers support and advance said stamp, when severed and the gummed under face of the stamp is thoroughly moistened by contact with the lower roller. From said rollers the severed and moistened stamp is delivered between a third small roll 110 and the upper final feed roller 8, the latter being formed with a series of annular grooves 110^a which are engaged by annular ribs formed on the small roller 110, the effect of said ribs and said grooves being to straighten the stamp and to remove the curl caused by rolling the same, so that the stamp will more readily adhere to the envelope during its passage between the final feed rollers. A large gear 111 upon the shaft 9 drives a train of comparatively small gears

112 by which the feed rollers 108 and 110 are driven.

As a provision against theft of the stamps it is desirable to normally prevent access to the same. This is accomplished by the provision of a casing 114 which is hinged at 114^a to the upper edge of the extension plate 53^a and which is adapted to be swung downwardly against said plate to house the stamp reel 58 and the entire stamp feed mechanism, said casing being provided with a large front window 114^b through which the operation of the stamp feed mechanism may be inspected and being further provided with the relatively small top window 114^c through which the counter 85 may be read. A suitable lock 114^d is carried by the extension plate 53^a for engagement with said casing to maintain the same normally in its position of use, shown in Figures 2 and 3.

Since it is at times desirable to seal a quantity of envelopes without stamping the same, a provision is made for adjusting the tripping arm 106 out of its position of use. Thus there is mounted adjacent the rock shaft 103 a smaller rock shaft 116 which is likewise journaled in the side plates 2 and 3 and projects beyond the former to receive a milled actuating head 117. Adjacent the tripping plate 105, an arm 118 is mounted fast upon the rock shaft 116 and terminally carries a pin 119, which pin upon a slight rocking movement of the shaft 116 is engageable with a hooked hanger 120 downwardly projecting from the trip arm 106 for shifting said hanger and trip arm downwardly in opposition to the spring 107^a to a position moving said arm from the path of the envelope through the machine. This mechanism may also be used to prevent unauthorized feeding of the stamps from the reel 58, and to this end there is provided upon the rock shaft 116 adjacent the side plate 3 an arm 121, beveled to ride over a yieldable detent 122 as the shaft 116 is being rocked to shift the trip arm 106 downwardly. The member 122, after the arm 121 has ridden thereover, projects to prevent retraction of said arm and is thus adapted to hold the trip arm 106 in lowered position. The locking member 122 is formed by the bent extremity of a wire arm 123, said extremity projecting through a small aperture 124 in the plate 3. Another portion of the wire forming the arm 123 functions as a rock shaft 125, the same being vertically mounted upon the outer face of the plate 3, and being acted upon by a spring 126 tending to project the locking member 122 through the aperture 124. The wire forming the rock shaft 125 is offset just above said rock shaft to pass through an opening 127 in the extension plate 53^a. Adjacent the inner face of said extension plate said wire is formed with a handle portion 128 which lies within the

110 115 120 125 130

casing 114 when the latter is in its closed position. Thus, when said casing is locked no access may be had to handle member 128 which must be actuated to effect a rocking 5 of the shaft 125 in order to retract the locking member 122 out of engagement with the arm 121 so as to permit the trip arm 106 to be raised by its spring 107^a into its position for engagement by the envelopes.

10 In the operation of the described machine a pile of the envelopes to be fed therethrough is first arranged upon the feed table 16, as is shown in Fig. 4, the flap of each envelope overlapping that of the underlying 15 envelope and the lowermost flap overlapping the guide plate 23. The larger guide plate 24 is adjusted at a distance from the plate 23 substantially equal to the width of said envelopes, and the pin 29 is adjusted 20 in the slot 30 according to the length of said envelopes so as to support their rear ends at a proper elevation. The operator then turns the crank 32, communicating rotation to all of the feed rollers and also 25 the flap moistening disc 37. Owing to the inclination of the pile of envelopes, the bottom one thereof tends to slide between the initial feed rollers 6 and the guide finger 17, an automatic successive delivery of the 30 envelopes to said feed rolls thus being provided for. The frictional action of the feed rolls 6 upon the bottom surface of any envelope is sufficiently greater than that of the rubber brush 22 upon the top surface of 35 the envelope to avoid any retardation of the envelope by said brush. In case, however, two or more envelopes tend to feed together past the rolls 6 this will be prevented by the brush 22, the frictional stress exerted 40 by the same upon the super-posed envelopes being sufficient to hold the same back. The table 16 guides each envelope from the initial rolls 6 to the first pair of intermediate rolls 11, and during this travel the edge of 45 the table 16 adjacent the plate 3 guides the flap of the advancing envelope so that the same may engage beneath the moistening disc 37. While the gummed surface of the flap is being pressed against the moist under- 50 face of said disc by the spring fingers 44, the advance of the envelope is being effected by the rollers 11. After disengaging from said disc and said fingers the flap is gradually turned up to approximately horizontal 55 position by the guide strip 50. After the front edge of an advancing envelope has travelled slightly beyond the second pair of intermediate feed rollers 12, said edge encounters the upper extremity of the trip 60 arm 106, assuming that said arm is in its raised position. As the envelope continues to advance, said arm is rocked forwardly and downwardly by the envelope, correspondingly rocking the trip plate 105 and the shaft 103. During this rocking move- 65 ment the arm 102 on said rock shaft shifts the engaged end of the bell crank lever 98, downwardly and the resultant rocking of said lever moves the finger 100 sufficiently away from the clutch member 94 to clear 70 the pin 100^a, thus permitting the spring 97 to engage said clutch member with the clutch member 95^a. Upon a very slight further advance of the envelope, after accomplishing the described result, the trip arm 75 106 assumes such an inclination as to disengage its upper extremity from the forward end of the advancing envelope, and thereupon the spring 104 effects a return rocking movement of the arm 102, shaft 103 and trip plate 105, bringing the same to their normal positions. This return movement carries the trip arm 106 back to a vertical position, but the same is held downwardly deflected by the envelope in opposition to the 80 spring 107^a. Immediately after the envelope has sufficiently advanced to disengage its rear edge from said trip arm, the latter is raised by the spring 107^a and is thus ready for engagement by the next advancing envelope. As the clutch member 94 shifts into engagement with the clutch member 95^a the pin 100^a is carried beneath 85 the finger 100 so that upon release of the lever by the arm 102 there can be no initial interference by the upper end of said lever with rotation of said clutch member. The clutch connection remains closed while the eccentric 92 is driven through one complete 90 revolution, being opened upon completion of such movement by a reengagement of the pin 100^a with the finger 100, the taper of said finger tending to deflect said pin and the clutch member 94 away from the clutch member 95^a. While the eccentric 92 is making the described revolution, the carriage 100 is being actuated through the connecting rod 90 and the pin 88, being first advanced toward the delivery end of the machine a 105 distance slightly greater than the width of one of the stamps of the strip 55 and being then returned to its initial position. In said position of the carriage the spring fingers 69 bear upon the stamp strip 55 slightly in back of the second stamp from the end of 110 the strip. Immediately after each advance of the carriage has begun, therefore, the down-turned ends 69^a of said fingers enter into engagement with the second line of perforations 70^a from the end of the stamp strip, causing the strip to participate in the 115 forward travel of the carriage. Owing to the restraint exerted upon the bell crank 77, 79 by engagement of its long arm 77 with the pin 78^a, a rocking of said bell crank results from the travel of the carriage, the short arm 79 being swung downwardly 120 as the carriage advances and acting through the dog 80 upon the knife 73 to lower the 125 same. Thus, said knife is caused to sever 130

the end stamp from the strip shortly before completion of advance movement of the carriage and immediately subsequent to engagement of said stamp by the two small feed rolls 108. As has heretofore been explained the action of the cam strip 82 upon the pin 81 effects a disengagement of the spring fingers 69 from the stamp strip 55, simultaneously with engagement of said strip by the knife 73. Preferably the cutting edge of said knife inclines slightly to the horizontal so as to slightly prolong the cutting operation and thus afford ample opportunity for disengagement of the spring fingers 69 from the strip during such operation. The stamp strip does not participate in the return movement of the carriage, since during such movement the pin 81 rides upon the pivotal cam member 83, the spring fingers 69 being thus held disengaged from the stamp strip. Just prior to completion of the rearward movement of the carriage said pin 81 rides clear of the cam member 83, permitting the sheet metal frame 68 to swing downwardly and to establish the normal position of the spring fingers 69 in engagement with the stamp strip just in back of the second line of perforations from the end of said strip.

30 The advance of the envelope to the final feed rolls 8 and 8^a is so timed with respect to the advance of the severed stamp to said rolls that during the passage of stamps and envelopes between said rollers the former will be affixed to the latter in the proper position. As has heretofore been explained, moistening of the severed stamps is effected during passage thereof between the small feed rolls 108, the lowermost of which is 40 partially immersed in water contained by the tank 109. The final feed rollers 8 and 8^a, in addition to affixing the moistened stamp to the envelope, serve also to press the moistened flap into firm contact with the 45 body of envelope so as to seal said flap.

When it is desired to employ the described machine only for sealing envelopes without applying any stamps thereto, the operator by means of the milled head 117 rocks the shaft 116 in the direction of the arrow (Figure 7) thereby engaging the pin 119 on the arm 118 with the hanger 120 and sufficiently lowering the trip arm 106 to remove the same from the path of travel of the envelope 50 through the machine. Said trip arm and rock shaft are held in the described position in opposition to the spring 107^a due to engagement of the locking arm 121 with the detent or retainer 122, formed upon the end 55 of the wire arm 123. When it is desired to release the arm 121 from the detent 122, the operator exerts pressure upon the extremity of the handle 128 thus rocking the wire rock shaft 125 sufficiently to disengage 60 the detent from said arm.

By the employment of the detachable guide members 60, 61, the arrangement of a stamp strip in a position to be intermittently advanced by the carriage 56 is greatly facilitated. In applying the strip to the 70 guide member, after the latter has been detached from the bracket 53, the leaf spring member 61 is detached from the bottom member 60 of the guide member, and the end portion of the stamp strip is disposed upon said member 60 between the side flanges 63 thereof. The spring 61 is then again attached to the member 60 so as to bear upon the stamp strip and create the 75 desired frictional resistance to movement of said strip. The guide member is then re-engaged with the bracket 53 and the strip is adjusted until the second line of perforations from the end thereof lies slightly in advance of the downturned ends 69^a of the 80 spring wire fingers 69. The thumb rest 71 on the metal frame 68 permits said wire fingers to be readily raised clear of the stamp strip while the latter is being adjusted. It is to be noted that in case any 85 initial error is made in adjusting the stamp strip relative to the carriage, this will be at once automatically corrected, since the feed fingers can only engage the strip upon a line of perforations thereof and the knife is so spaced from the feed fingers as to necessarily cut upon the line of perforations next in advance of that engaged by said fingers.

What I claim as my invention is:

1. In a device of the character described, the combination with a work feeding roller, of a cooperating non-rotative work feeding member, a bracket projecting above said roller and providing a support for said cooperating member, and a guide member for the work adjustably mounted upon said bracket.

2. A stamp strip feeding mechanism, comprising a reciprocatory carriage, a stationary mounting for said carriage upon which mounting the stamp strip to be fed is adapted to be extended, means for engaging the stamp strip mounted upon said carriage, a knife mounted upon the carriage for successively severing the stamps from the stamp strip, and mechanism actuatable by the advance of the carriage for engaging said knife with the stamp strip during the latter part of said advance.

3. A stamp feeding mechanism, comprising a carriage, a stationary mounting for said carriage upon which the stamp strip to be fed is adapted to be extended, means upon the carriage for advancing the stamp strip in common with the carriage, a knife mounted upon the carriage for successively severing the stamps from said strip, and a bell crank pivoted upon the carriage having one arm adapted to exert a down pressure

upon said knife, and the other restrained so as to effect a rocking of the bell crank when the carriage is reciprocated.

4. In a device of the character described, 5 the combination with envelope sealing mechanism and stamp feeding mechanism, of a clutch through which said stamp feeding mechanism is adapted to be driven by the envelope feeding mechanism, said clutch 10 being normally thrown out, a trip member arranged in the path of the advancing envelope and actuatable by the envelope to establish a drive to the stamp feeding mechanism through the clutch, and means for holding said trip member adjusted out of the path of the advancing envelope.

5. In a device of the character described, 20 the combination with an envelope feeding mechanism and a stamp feeding mechanism, of a clutch normally thrown out, through which the stamp feed mechanism is adapted to be driven in common with the envelope feed mechanism, a trip member arranged in the path of the advancing envelope and actuatable by the latter to establish a drive to the stamp feeding mechanism through the clutch, mechanism for adjusting said trip member out of the path of the advancing envelope, and a locking means for said 25 mechanism maintaining the restraining effect thereof upon said trip member.

6. In a device of the character described, 35 the combination with an envelope feeding mechanism and a stamp feeding mechanism, of a clutch through which the latter mechanism is adapted to be driven, a casing for enclosing the stamp feeding mechanism, means for locking said casing, a trip member in the path of the advancing envelopes 40 and actuatable by the latter to establish a drive through said clutch to the stamp feeding mechanism, said member being adjustable out of the path of said envelopes, and means for locking said trip member out of 45 the path of the envelopes operable from within said casing.

7. In a device of the character described, 50 the combination with an envelope feeding mechanism and a stamp feeding mechanism, of a clutch, normally thrown out, through which the stamp feeding mechanism is adapted to be driven in common with the envelope feeding mechanism, a spring tending to close said clutch, a lever resisting closing of the clutch, a rock shaft, a trip member mounted upon said rock shaft to actuate the same and extending into the path of the advancing envelopes to be re-

spectively actuated thereby, and an arm carried by said rock shaft acting upon said lever to disengage the same from said clutch when said rock shaft is actuated by an advancing envelope.

8. In a device of the character described, 60 the combination with a pair of side plates, one of which has an extension above the other, of a plurality of envelope feeding rollers journaled in said side plates, a stamp feeding mechanism mounted upon said upward extension of one of the side plates, a 65 casing hinged to said extension and adapted in one position to enclose said stamp feeding mechanism, means for locking said casing, and means for moistening the stamps and timing the feed thereof to insure a 70 proper affixing of said stamp to the envelope in passing through certain of said feed rollers.

9. A stamp strip feeding mechanism, 75 comprising a reciprocatory carriage, a stationary mounting for said carriage upon which mounting the stamp strip to be fed is adapted to extend, means mounted upon said carriage for engaging the stamp strip, a knife mounted upon the carriage for successively severing the stamps from the strip, and mechanism actuatable in timed relation to the carriage for actuating said knife.

10. The combination with mechanism for 80 operating on an envelope, and means for advancing envelopes to said mechanism, a clutch through which said mechanism is driven, said clutch being normally thrown out, trip mechanism for closing said clutch, 85 under control of the advancing envelopes, and means for exercising a restraining control upon said trip mechanism for preventing effective response thereof to the envelopes.

11. In a device of the character described, 90 the combination with envelope sealing mechanism and stamp feeding mechanism, of a clutch through which the stamp feeding mechanism is adapted to be driven, said clutch being normally thrown out, trip mechanism actuatable by the advancing envelopes for establishing a drive to the stamp feeding mechanism through said clutch, and means for establishing a restrained position 95 of the trip mechanism preventing effective response thereof to the envelopes.

In testimony whereof I affix my signature.

GUY E. TIFFT.
